(57) **CLAIM**

We claim the ornamental design for an information handling system communication device, as shown and described.

DESCRIPTION

FIG. 1 is a front perspective view of the information handling system communication device comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and

FIG. 7 is a bottom view thereof; and,

FIG. 8 is a detailed view as indicated in FIG. 1.

The broken lines shown in the drawings, illustrate portions of the information handling system communication device that form no part of the claimed design. The broken line squares surrounding the detail in FIG. 1 and FIG. 8 are for annotation purposes only and form no part thereof.
